UNITED STATES PATENT OFFICE.

HARRIS I. McMAHAN, OF ST. PAUL, MINNESOTA, ASSIGNOR TO ST. PAUL JOURNAL BOX COMPANY, OF ST. PAUL, MINNESOTA.

CAR-AXLE-BOX LID.

No. 894,896.

Specification of Letters Patent.

Patented Aug. 4, 1908.

Application filed June 13, 1907. Serial No. 378,746.

To all whom it may concern:

Be it known that I, HARRIS I. McMAHAN, a citizen of the United States, residing at St. Paul, in the county of Ramsey and State of Minnesota, have invented certain new and useful Improvements in Car-Axle-Box Lids; and I do hereby declare the following to be a full, clear, and exact description of the invention, such as will enable others skilled in the art to which it appertains to make and use the same.

My invention has for its object to provide an improved car axle box lid, and to this end it consists of the novel devices and combinations of devices hereinafter described and defined in the claims.

In the accompanying drawings which illustrate the invention, like characters indicate like parts throughout the several views.

20 Referring to the drawings, Figure 1 is a view in side elevation showing a car axle box with my improved lid applied thereto. Fig. 2 is a front elevation of the parts shown in Fig. 1. Fig. 3 is a vertical section taken on the line $x^3 x^3$ of Fig. 2. Fig. 4 is a detail view in elevation, looking at the inner face of the lid and showing the same removed from the box. Fig. 5 is a detail view looking at the inner face of the lock bar which co-operates 25 with the lid. Fig. 6 is a detail view in side elevation of the lock bar shown in Fig. 5, with the intermediate portion of the lock bolt shown in section. Fig. 7 is a vertical section taken on the line $x^7 x^7$ of Fig. 2, but 30 on an enlarged scale. Fig. 8 is a horizontal section taken on the line $x^8 x^8$ of Fig. 2; and Fig. 9 is a detail view, on an enlarged scale, showing the so-called lock bolt.

The journal box 1 is provided at its front 40 face with an annular lid seat 2, the rim of which is preferably rounded in cross section. A hinge bolt or shaft 3 is rigidly supported by heavy lugs 4 located on the upper portion of the box 1 and, as shown, cast integral 45 therewith. The intermediate portion of this hinge bolt 3 is flattened as shown at 3^a .

The lid 5 is provided on its inner face near its outer edge with an annular groove 6 that is adapted to closely fit the rounded face of the annular lid seat 2 of the box, and it is provided with a pair of heavy hinge lugs 7, the upper ends of which are pivotally mounted on the round portion of the hinge bolt 3 between the hinge lugs 4 of the box. The

perforations in the lugs 7 through which the hinge bolt 3 is passed are elongated or enlarged so as to loosely fit upon said bolt and to permit the lid to adapt itself to the annular lid seat 2 when pressed against the box. The so-called hinge lugs 7 are extended 60 downward or outward across the outer face of the lid to form guard ribs 7 a that are beveled in opposite directions, as best shown in Fig. 8.

Located between the guard flanges 7 a and the hinge lugs 7, and pivotally mounted at its upper end on the flattened or angular portion 3 a of the non-rotary hinge bolt 3 is a so-called lock bar 8, the depending free end of which is adapted to be engaged with and disengaged from an up-turned lock rib or detent 9 formed on the lower outer portion of the axle box. In its upper end, the lock bar 8 is provided with an elongated seat 8 a having an enlarged intermediate portion. When 75 this bar 8 is moved with the enlarged intermediate portion of its seat 8 a into line with the hinge bolt, it may be moved pivotally from the position shown by full lines into the position shown by dotted lines in Fig. 3, and 80 vice versa. When it is turned down as shown by full lines in Fig. 3, the upper extremity of the seat 8 a permits the free end of the bar to be dropped into engagement with the lock lug 9 of the box; and when the said 85 lever is moved upward into the position shown by dotted lines and is then slid slightly endwise toward the hinge bolt, the inner extremity of the seat 8 a engages the flattened portion 3 a of said hinge bolt and 90 thereby locks or secures the said arm in its elevated position, in which position it is adapted to support and hold the lid 5 in its open position, shown in Fig. 3. To adapt 95 the arm 8 to hold the lid in its open position as just stated, it is provided with lateral projections or lugs 10 that engage under ribs 11 on the inner sides of the lid lugs 7, as best shown in Fig. 7.

At its intermediate portion, the lock bar 8 100 is provided with laterally spaced inwardly projecting ears 12 through which extends a short shaft 13 having at one end an operating lever 14. Rigidly secured to the rock shaft 13 between the ears 12, is a cam or eccentric 105 block 15 that is adapted to operate upon a centrally located bearing surface 5 a of the lid 5. By reference to Fig. 2 it will be seen

that the left hand guard flange 7^a is cut away, as shown, at 7^b to afford clearance for the cam operating lever 14.

When the lid is turned against the face of the box and the lock bar 8, at its lower end, is engaged with the lock lug 9, the said lid may be tightly clamped against the said lid 2 by a downward movement of the lever 14 into the position shown in Fig. 3, which lever 10 movement forces the projecting portion of the cam 15 against the central portion of the lid. At this time the lock bar 8, of course, affords a base of reaction for said cam.

When the lever 14 is moved upward, the 15 flattened or inner portion of the cam 15 is thrown adjacent to the lid, and the lid is then loosened and given sufficient play to permit the same and the lock bar to be moved upward far enough to carry the free end of the 20 said lock bar above the lock lug 9, whereupon, as is evident, the said lock bar and lid may be moved into their uppermost positions shown by dotted lines in Fig. 3.

When the lid is locked to the box, the cam 25 actuating lock lever 14 is forced into the notch or seat 7^b and is then protected by the bar 8, and the beveled guard ribs 7^a, so that it can not be caught or broken by flying objects or obstructions along the line of travel. 30 It will also be noted that the beveled guard flanges 7^a protect the lock bar 8 and together therewith form an approximately smooth exterior portion on the outer face of the lid and box. The said lock lever 14 may be easily 35 reached and pulled outward by the ordinary packing hook which is always carried by persons charged with the inspection and care of car axle boxes.

What I claim is:

40 1. The combination with an axle box, of a lid and a lock bar independently hinged to said box, the said lock bar having interlocking engagement with the box at its free end, and a lock device arranged to work between 45 the intermediate portions of said lock bar and lid to press the latter against the seat on the box, substantially as described.

2. The combination with an axle box and a lid hinged thereto, of a lock bar hinged to 50 said box and having interlocking engagement therewith at its free end, and a lever actuated cam or eccentric mounted on the intermediate portion of said lock bar and engageable with the intermediate portion of 55 said lid to press the same against its seat on the box, and which cam is adapted to be thrown into an operative position beyond its dead center or point of greatest pressure on the lid, whereby it will remain set in its 60 locked position substantially as described.

3. The combination with a car axle box, and a hinge both secured thereto of a lid and

a lock bar pivoted to said hinge bolt said lid having a marginal groove that fits a projecting seat on the box, and said lock bar having 65 interlocking engagement with said box at its free end when lowered and having interlocking engagement at its other end with the supporting hinge bolt when raised, a lock device reacting against the intermediate portions of 70 said lock bar and lid to press the latter against its seat on the box when said lid and bar are lowered, and a connection between said lock bar and lid whereby said bar will support the said lid independent of said lock 75 device in an open position, substantially as described.

4. The combination with an axle box 1 having an annular lid seat 2 and hinge lugs 4, of a hinge bolt 3 fixed to said lugs 4 and having a flattened intermediate portion 3^a, a lid 5 having lugs 7 loosely pivoted on said hinge bolt and having a groove 6 engageable with said lid seat 2, a lock bar 8 having an elongated seat 8^a adapting it to move pivotally 85 on and to be interlocked with the flattened portion 3^a of said hinge bolt, and having interlocking engagement with the box at its free end when lowered, a lever actuated cam or eccentric on the intermediate portion of 90 said bar bearing on the intermediate portion of said lid to press the same against its seat on the box, and a connection between said bar and lid for causing the former to support the latter in a raised position, substantially 95 as described.

5. The combination with an axle box, of a lock bar and a lid independently pivoted to the box, said lock bar having interlocking engagement with the box at its free end, and the said lid having a groove in which the main body portion of said bar lies approximately flush, and a lock device interposed between the intermediate portions of said lock bar and lid for yieldingly pressing the 105 latter against its seat on the box, substantially as described.

6. The combination with an axle box, of a lock bar and lid independently pivoted thereto, a lock device interposed between the intermediate portions of said lock bar and lid for pressing the latter against its seat on the box, the said lock bar having a connection to said lid which is independent of said lock device and operates to hold the lid in a raised 115 position when said lock bar is raised, substantially as described.

In testimony whereof I affix my signature in presence of two witnesses.

HARRIS I. McMAHAN.
